UNITED STATES PATENT OFFICE.

WILLIAM H. DE WICK, OF BROOKLYN, NEW YORK.

STRINGED MUSICAL INSTRUMENT.

981,393.

Specification of Letters Patent. Patented Jan. 10, 1911.

Application filed April 20, 1909. Serial No. 491,121.

To all whom it may concern:

Be it known that I, WILLIAM H. DE WICK, a citizen of the United States, residing at Brooklyn, in the county of Kings and 5 State of New York, have invented certain new and useful Improvements in Stringed Musical Instruments; and I do hereby declare the following to be a full, clear, and exact description of the invention, such as 10 will enable others skilled in the art to which it appertains to make and use the same.

This invention relates to musical instruments of the stringed variety and has for an object to provide an instrument of improved 15 form and construction whereby improved tone is secured and also additional physical strength.

A further object of the invention is to provide a stringed musical instrument having 20 a body with a neck disposed at an inclination to the sounding board of the body with the inner end of the neck supported by a wedge-shaped piece in such position that the strings are elevated from the sounding 25 board requiring a higher bridge.

With these and other objects in view, the invention comprises certain novel constructions, combinations and arrangements of parts, as will be hereinafter fully described 30 and claimed.

In the drawings:—Figure 1 is a view of the improved instrument in top plan. Fig. 2 is a view of the instrument in side elevation. Fig. 3 is a section longitudinally of the neck 35 through the portion joined to the body showing the sounding board and rim in section.

Like characters of reference designate corresponding parts throughout the several views.

40 The improved musical instrument, forming the subject-matter of this application, is provided with a cylindrical body composed of the rim 10, the sounding board 11, a back 12, the sounding board and back being preferably parallel planes. To the body is secured the neck 13 having a head 14 with any usual or approved means for exerting tension upon the strings 15 which are secured to the body at the side opposite the joining 45 with the neck by any approved form of tail piece 16.

The finger board 17 is secured to the neck in substantially the usual manner and extends beyond the neck and over the sounding board of the instrument from which it is spaced at its extremity by a wedge-shaped member 18. The wedge 18 provides a support for the neck where it extends over the sounding board so that a bridge 19 is required of more than the ordinary height. 55 It is found that it is desirable to raise the strings above the sounding board of the instrument giving thereby a more desirable tone. The object of the wedge is to fill the space between the sounding and finger 60 boards thereby forming a solid finger board from end to end so as to produce a more perfect and increased vibration of the instrument, the instrument having a higher bridge 65 than is ordinarily used, and a guard plate or sounding board protector is not necessary. It is also found that by producing the rim 10 as a circular hoop of considerable thickness as indicated in section at Fig. 3 the vibrations of the instrument are 70 confined very largely to the sounding board whereby improved tone is also secured, the sounding board, of course, being made of the usual wood employed for sounding 75 boards and the like.

By using a circular sound board supported by a hoop of this kind only 3 sound bars 20 are required which can be so arranged that the main bar may be placed back of the bridge, a feature found in no other instrument of this description where three sound 80 bars are used. This arrangement results in an improved tone. The hoop is one piece into which a block is fitted for the purpose of forming a base in which to set the neck. 85

By the employment of a thick cylindrical rim 10 bracing within the instrument to support the sounding board is done away with thereby eliminating some of the portions of the instrument which are likely to 90 deleteriously affect the tone.

While the instrument is shown in the drawings as strung similarly to a mandolin it is to be understood that such stringing is only conventional and that any approved 100 or desired form of stringing may be employed or substituted.

What I claim is:—

A stringed instrument comprising a body with a sounding board, a neck secured to the body, its upper face being inclined back-

5 ward from the plane of the sounding board, a finger board carried on said face and extending over and above the sounding board, a wedge of a length and width equal to that

of said extended end inserted between said board and said end.

In testimony whereof I affix my signature in presence of two witnesses.

WILLIAM H. DE WICK.
